SANDAL

Jack Stein, New York, N. Y.

Application February 28, 1951, Serial No. 14,339

Term of patent 3½ years

(Cl. D7—7)

To all whom it may concern:

Be it known that I, Jack Stein, a citizen of the United States of America, and a resident of the city of New York, in the county of Kings, and State of New York, have invented a new, original, and ornamental Design for Sandal, of which the following is a specification, reference being had to the accompanying drawing, forming a part thereof.

Fig. 1 is a perspective view of the sandal showing my new design; and

Fig. 2 is a side view thereof.

I claim:

The ornamental design for a sandal, substantially as shown.

JACK STEIN.
